UNITED STATES PATENT OFFICE.

ARTHUR COLEMAN, OF KANSAS CITY, MISSOURI.

CARBURETING VAPORIZER.

Application filed April 7, 1924. Serial No. 704,689.

This invention relates to carbureting vaporizers and the particular object of the invention is to vaporize the liquid hydrocarbon content of the fuel mixture by heat before it combines with the air content necessary to support combustion. I am aware that so-called hot points, stoves and the like have been utilized for preheating the fuel mixture before it is received into the combustion chamber of the internal combustion engine but my invention differs essentially from these known devices in that the liquid hydrocarbon content of the fuel mixture is not only heated but raised to a very high temperature whereby it is vaporized, at a local point without heating the oil below the point of contact with the air and the preferred embodiment of my invention is such that relatively low grade liquid hydrocarbons can be used as fuel in internal combustion engines although I prefer to utilize the invention with the commercial grade of gasoline, the specific gravity of which is somewhere above 50° Baumé.

Means is provided for utilizing the heat from the exhaust manifold of the engine for heating the hydrocarbon before it mixes with the air and means is provided for inducing an abnormal suction in the intake manifold so that a relatively large volume of the mixture can be drawn into the combustion chamber and I have found that by raising the temperature of the liquid hydrocarbon to a point where it is vaporized preparatory to mixing it with the air that the ratio between the hydrocarbon content and the air content of the mixture can be materially reduced, that is not so large a proportion of the hydrocarbon content will be required as is ordinarily supposed to be necessary with known types of carburetors; therefore there is an appreciable saving in the consumption of the liquid content of the fuel mixture.

The details of the preferred embodiment of my invention by which I accomplish the desired result will be apparent by reference to the following description in connection with the accompanying drawings in which

Fig. 1 is an elevational view of an internal combustion motor to which my invention is applied.

Fig. 2 is a vertical cross sectional view through the carburetor and through part of the exhaust manifold, and

Fig. 3 is a sectional view on the line 3—3 of Fig. 2.

In carrying out my invention some means must be provided for vaporizing the hydrocarbon liquid before it comes into contact with the air to form the combustible mixture and I have found that this can be admirably accomplished by providing the exhaust manifold 1 of the internal combustion engine 2 with a ring-shaped passageway 3 having a central opening 4, the wall 5 of which conducts heat to the constricted portion or neck 6 of the carburetor casing 7. The carburetor casing has a conical lower end portion 8 which merges into the collar-like constricted portion 6 seated within the wall 5. The top of the casing 7 is closed by a removable flanged mixing chamber 9 in the form of a tube having a constricted truncated conical lower end 10 with an opening 11 in axial alignment with the needle valve 12 passing through the opening 13 in the valve seat 14 on the end of the supply tube 15 through which the needle valve stem 16 passes, the needle valve being packed by a packing gland 17 in the usual manner. Hydrocarbon fluid is admitted to the tubular member 15 from a suitable source of supply through a pipe 18 having a valve seat 19 adapted to be closed by a check valve 20 in which is a weight 21 of appropriate construction which will tend to submerge the valve 20 so that it will be seated except when the suction of the piston on the intake stroke raises it as will be readily understood.

The wall of the mixing chamber 9 is spaced from the wall of the casing 7. The casing 7 is provided with an air inlet opening 22 surrounding a perforate tubular sleeve 23 on the rigid tube 24 communicating with the mixing chamber 9. The sleeve 23 is a valve provided with ports 25 which may register with ports 26 in the tube 24. The sleeve valve can be turned by a lever 30 and it may be operated from the dash board of a motor vehicle by suitable connections as will be well understood.

The effective port area of the mixing chamber 9, that is its area as compared with the intake manifold 31, may be varied by the valve 32 on stem 33 passing through the members 7 and 9, the shaft or stem 33 carrying a lever 34 by means of which the valve can be operated. The valve 20 moves in the valve casing 35.

When the parts are assembled, the needle valve 23 will be closed and the valve 32 will be in full open position. Then when the en-

gine is turned over a powerful suction will draw gasoline or other hydrocarbon fuel and some air through the mixing chamber 9 into the combustion chamber of the engine because if the sleeve valve 23 is closed, it will act as a "choke". After the engine manifold 1 heats up due to the passage of hot gaseous products of combustion through it, the ring-shaped passageway 3 will heat the valve seat 13 to a relatively high temperature, for example to about a cherry red color. The gasoline passing the needle valve will come into contact with the hot valve seat so that it is vaporized by the high temperature into a fog-like vapor and so that it will mix with air passing through the opening 22 and through the passageway 36 through the opening 11 and into the mixing chamber. By the time the needle valve seat becomes hot enough to vaporize the oil, the choke, that is the sleeve-like valve 23, should be open to admit atmospheric air into the mixing chamber above the point at which the hydrocarbon vapor and initial air is mixed. The admitted cool atmospheric air passing into the mixing chamber 9 through the tubular member 24 will tend to reduce the temperature of the vaporized fuel mixture so that it will enter the combustion chamber at a much lower temperature than that at which it was mixed. The reason for this is that the heated or vaporized hydrocarbon content of the fuel mixture will expand considerably in volume due to the heating thereof. This volume will of course be contracted when it mixes with the initial air admitted through opening 22, and it will be finally reduced in volume by the incoming air admitted through tube 24. Consequently a relatively cool dense mixture will be received in the combustion chamber permitting the fuel charge to be compressed to greater density than would be possible were the constituents of the fuel mixture admitted to the combustion chamber of the cylinder in a rarefied or expanded state and since the liquid content is first flashed into vapor at a relatively high temperature so that it will be thoroughly vaporized then mixed with air and finally cooled, it will be apparent that the power generated in each cylinder or the force exerted against each piston will be in excess of such force exerted against the piston of a normal internal combustion engine.

Attention is called to the fact that since the hydrocarbon content of the mixture is thoroughly vaporized before coming into contact with the air so that a practically perfect mixture is provided, that the consumption of gasoline or high grade naphtha will be considerably less per horse-power hour than has been the case with the ordinary types of carburetors now upon the market.

In actual tests, I have obtained more than double the efficiency of an ordinary carburetor by using my device on a standard engine

with a standard carburetor, the test running over a considerable period and this increase in efficiency I attribute to the fact that the liquid content of the fuel mixture passes over or contacts with a very hot spot and is vaporized prior to coming into contact with the air which is introduced to support combustion and the increased efficiency I believe is due in part to the fact that the mixture is relatively cool at the time it enters the combustion chamber of the internal combustion engine.

The check valve is provided to prevent the heated oil from passing back through the pipe 18 but it will be noted that the pipe 15 is below the exhaust manifold ring so that it will remain comparatively cool, the sudden heating of the oil taking place at a seat 14. It will further be noted that the air which passes through the opening 22 through the space 36 through the opening 11 into the mixing chamber will be more or less agitated so that it will thoroughly commingle and combine with the hydrocarbon content of the mixture before it passes into the intake manifold.

By reference to the drawings it will be noted that the relationship of the tube 15 with respect to the portion 6 from which heat is communicated is such that the gasoline in the tube 15 will not be raised to a boiling or vaporizing temperature. Consequently there will be a uniform flow of gasoline to the valve seat at all times to provide a uniform hydrocarbon feed to the hot zone. This is important in the control of the vaporizer because if the liquid in tube 15 became hot enough to vaporize or boil, the suction stroke of the piston of the engine would not cause the admission of a uniform quantity of hydrocarbon because if bubbles were formed in the tube 15 due to boiling of the gasoline, one intake stroke of the piston might admit a full charge of hydrocarbon through the constricted portion 5 and the next intake stroke of another piston might throw a bubble through the valve seat which would impoverish the mixture. Consequently there would be a more or less haphazard control of the gasoline but by maintaining the tube 15 cool enough to prevent the gasoline from boiling, a uniform quantity of gasoline will flow through the valve seat for the needle valve at each intake stroke of the piston, this being obviously necessary for the highest efficiency of the carbureting vaporizer.

What I claim and desire to secure by Letters Patent is:

1. A carbureting vaporizer comprising a tubular casing having a conical lower end terminating in a valve seat receiving collar, a pipe for supplying hydrocarbon fluid to the casing provided with a valve seat receivable in the collar and having a port opening connecting the pipe with the casing, means for

- supplying heat to the collar and through it to the valve seat to cause hydrocarbon fluid to become vaporized in its passage through the valve seat, a needle valve for controlling the effective port area of said port opening, a tubular mixing chamber having a wall parallel with the wall of the casing and closing off the upper end of the casing, the mixing chamber having a constricted lower end with a central opening in a line with the opening surrounded by the valve seat, the casing having an air inlet port between its top and bottom, and the mixing chamber having an air inlet port between its top and bottom and a sleeved valve on the inlet port of the mixing chamber for controlling the effective port area thereof in combination with an exhaust manifold having a ring-shaped seat to receive the collar of the casing whereby heat from the exhaust manifold will be communicated to the valve seat.
2. A carbureting vaporizer comprising a tubular casing having a conical lower end terminating in a valve seat receiving collar, a pipe for supplying hydrocarbon fluid to the casing provided with a valve seat receivable in the collar and having a port opening connecting the pipe with the casing, means for supplying heat to the collar and through it to the valve seat to cause hydrocarbon fluid to become vaporized in its passage through said port opening, a valve for controlling the effective port area of the valve seat and thereby controlling the vaporization of the hydrocarbon during its passage through the valve seat, a tubular mixing chamber having a wall parallel with the wall of the casing and closing off that part of the casing at one end surrounding the tubular mixing chamber, the mixing chamber having a constricted lower end with a central opening in line with the opening surrounded by the valve seat, the casing having an air inlet port between its top and bottom, the mixing chamber having a tubular inlet port surrounded by the air inlet port of the casing provided with perforations, and a sleeved valve on the inlet port of the mixing chamber spaced from the wall of the inlet port for the casing, the sleeved valve having perforations adapted to register with the perforations in the tubular inlet port of the mixing chamber, and the valve being movable for controlling the effective port areas of the perforations in the port for the tubular mixing chamber.

In testimony whereof I affix my signature.

ARTHUR COLEMAN.
